UNITED STATES PATENT OFFICE.

HENRY ARIENS, OF BRILLION, WISCONSIN, ASSIGNOR TO BRILLION IRON WORKS, OF BRILLION, WISCONSIN.

GROUND-PULVERIZER.

1,179,388.

Specification of Letters Patent. Patented Apr. 18, 1916.

Application filed December 6, 1915. Serial No. 65,223.

To all whom it may concern:

Be it known that I, HENRY ARIENS, a citizen of the United States, and resident of Brillion, in the county of Calumet and State 5 of Wisconsin, have invented certain new and useful Improvements in Ground-Pulverizers; and I do hereby declare that the following is a full, clear, and exact description thereof.

10 This invention relates to new and useful improvements in soil working apparatus and is more particularly directed to the provision of a pulverizer including a plurality of ground engaging cylinders.

15 It is primarily the object of the present invention to provide such a structure wherein the load of the frame and of the operator is distributed in such manner as to procure an exceedingly efficient operation.

20 It is further an object to provide in a pulverizer, wherein one of the rollers is of a toothed type, means whereby the load of said roller is imparted thereto in a resilient manner to protect it from damage or possible breakage due to engagement with 25 stones or the like.

With the above and other objects and advantages in view, the invention resides more particularly in the novel combination, arrangement and formation of parts more particularly hereinafter described and particularly pointed out in the appended 30 claims.

35 In the drawings: Figure 1 is a side elevation of a pulverizer constructed in accordance with the present invention. Fig. 2 is a top plan view thereof with portions broken away to more clearly disclose the structure. Fig. 3 is a detail sectional view taken 40 through the pivotal connection of the roller on the line 3—3 of Fig. 1.

Referring now more particularly to the accompanying drawings, there is provided a body frame including end castings 5 each in the form of a triangular frame, one of the sides of which is disposed horizontally to form the top of the casting, and is provided at its ends with inwardly extending flange portions 6, which flange portions are continued at the adjacent ends of the other sides of the frame to form means for securing respective ends of angle bars 7 which connect the castings. At the meeting ends of the depending sides of the castings is formed a head 8 which carries a bearing sleeve 9 in

which is journaled the shaft 10 of the forward roller 11, this roller comprising a series of disk members having their peripheries angular in cross-section and having their sides abutting to form substantially a cylinder provided with a spaced series of annular ribs. This general structure is disclosed in Patent No. 795327, granted July 25, 1905. As in this previous patent a draft tongue 12 is disposed transversely of and secured to the angle bars 7, and braces 13 are secured to the forward angle bar and to a plate 14 carried by the tongue forwardly of the frame. For pivotally mounting the rear toothed roller 15, a pair of angular bars 16, are provided which include relatively short arm sections enlarged to carry at their free end portions, sleeves 17 journaling the roller shaft 18. The upper portions of the rear depending sides of the end castings 5 are outwardly offset at 19 and the long arms of the bars 16 are pivoted on the inner faces of these offsets and extending forwardly thereof to have their ends lie adjacent arcuate ribs 20 carried on the outer faces of the forward sides of the castings, the curvature of each rib having the pivot of the arm as a radius. Each bar 16 and the respective casting head 8 are provided with hooks 21 having their bills extending in opposite directions and a relatively strong retractile spring 22 is carried by each pair of hooks.

The driver's seat 23 is carried by a bar 24 which extends from the rear of the draft tongue, this bar being braced by a link 25 intermediately secured thereto as by the clamp plates 26 and secured at its forward apertured end by engagement with the bight of a J-bolt 26, this J-bolt also carrying a link 27 which has its forward end upwardly offset and carrying the double-tree pin 28.

The rear roller 15 comprises a plurality of toothed disks 29 carried on hub members 30 and held spaced thereby so that said disks are disposed at the side edges of the disks of the forward rollers whereby they engage the ridges of ground formed by the forward rollers.

By the structure above described, it is seen that the entire weight of the body frame and of the draft tongue and of the driver is imparted to the forward roller 11, and that a desired portion of this weight is indirectly imparted to the rear roller 15 through the medium of the springs 22. As

the forward roller performs the most work it consequently carries the greater load. By positioning the toothed roller 15 rearwardly of the ribbed roller 11, it is noted that any 5 clogs or other hard lumps which are not pressed by the roller 11 will be however, disposed by said roller directly in the path of a respective disk of the roller 15 so that the teeth of said disk may act thereon to 10 break it up.

The roller 15 having its load resiliently imparted thereto may ride over stones without damage or danger of possible breakage to its teeth. As the forward ends of the 15 bars 16 are engageable with the ribs 20 throughout the possible movements, it is seen that the pivots of said bars are thereby relieved from strain due to lateral impulses imparted to the rear roller structure.

20 I claim:

1. A pulverizer comprising a seat and tongue carrying body frame, a roller carried by the frame, bars pivoted to the frame and extending rearwardly thereof with their 25 rear ends directed downwardly, a second roller carried by the said downwardly directed ends of the bars and retractile springs connecting said bars and the frame.

2. A pulverizer comprising a body frame, including pairs of depending end members, 30 a roller carried by said members, corresponding members of each pair having portions offset, angular bars each having one arm intermediately pivoted in a respective offset and extended adjacent the other re 35 spective depending member, a roller carried by the other arms of the bars and springs connecting said bars and the frame.

3. A pulverizer comprising a seat and tongue carrying body frame, a cylindrical 40 roller carried thereby, a series of annular ribs on the roller, a toothed ground engaging member pivotally carried by the frame rearwardly of the roller and having its teeth arranged in longitudinal alinement 45 with the base portions of the ribs, and means resiliently urging the said toothed member to the ground.

In testimony that I claim the foregoing I have hereunto set my hand at Brillion, in 50 the county of Calumet and State of Wisconsin, in the presence of two witnesses.

HENRY ARIENS.
